UNITED STATES PATENT OFFICE.

WILLIAM P. BIDDLE, OF KNOXVILLE, TENNESSEE.

CANOPY-SUPPORT.

SPECIFICATION forming part of Letters Patent No. 669,740, dated March 12, 1901.

Application filed May 21, 1900. Serial No. 17,359. (No model.)

To all whom it may concern:

Be it known that I, WILLIAM P. BIDDLE, a citizen of the United States, residing at Knoxville, in the county of Knox and State of Tennessee, have invented a new and useful Improvement in Canopy-Supports, of which the following is a specification.

My invention relates particularly to such canopy-supports as are applied to bedsteads for the support of a mosquito-netting adapted to extend over the entire bedstead.

The object of my invention is to provide a canopy-support which may be manufactured at a small cost and which may be easily applied to beds and other articles and readily manipulated so as to put the canopy into position for use or raise it and fold the netting at and above the head of the bed.

The improvement extends to features embodied in a hinged frame, to spring mechanism for supporting said frame, to means for securing said frame and spring mechanism to the bedstead, and to a vertical adjustable head portion of the support, which may also be secured by the means which secures said hinged frame and said spring mechanism to the bedstead.

In the accompanying drawings, Figure 1 is a side elevation showing my improved support applied to a bedstead. Fig. 2 is a detached view of the hinged frame. Fig. 3 is a detail view of one of the corners of said frame. Fig. 4 is a detail rear elevation showing a portion of the hinged frame, one of the lifting-springs, and a portion of the vertical adjustable head portion of the support, all secured to the head of the bedstead by a single plate or bracket. Fig. 5 is a side elevation of the parts shown in Fig. 4. Fig. 6 is a detail view showing the face of said plate or bracket which rests against the bedstead. Fig. 7 is a detail view showing the lifting-spring looking horizontally in a line parallel to the axis of the coil from the edge of the headboard opposite the edge to which said spring is attached. Fig. 8 is a view of said spring looking from the direction of the foot of the bed. Fig. 9 is a detail view showing the plate or bracket applied to a cylindric post of a metallic bedstead or similar article.

Referring first to Fig. 1 of said drawings, A is the body of a wooden bedstead B is the

headboard or head-frame, and C is the foot-board or foot-frame of said bedstead.

The canopy-support, as here shown, consists of two principal parts, the head-support D and the hinged frame E. Auxiliary to these parts are the lifting-spring F and the plate or bracket G, which secures said head-support, said hinged frame, and said lifting-spring to the headboard of the bed. Said lifting-spring and said plate G are duplicated on the side of the bedstead opposite the side shown in said Fig. 1.

The frame E is hinged to the plate G at G'. The lifting-spring F has one end adapted to engage the frame E, as by a sliding connection at E', said connection being preferably formed by bending the end of the spring F loosely around the adjacent arm of the frame E, so as to form a coil F'. The opposite end of said spring is folded to form a foot F², extending flatwise between the bedstead and the plate G. (See Figs. 4 and 7.) Screws g' and g² extend through said plate into the bedstead, thus clamping said foot between said plate and the bedstead. Between said foot and said coil F' said lifting-spring F is formed into one or more (the drawings show two) coils F³, resting in a plane to which said foot is lateral, said coils being on a horizontal axis parallel to and far enough forward of the plane of said foot to make said plane tangential to said coils. Said spring is so formed that the end bearing the coil F' is normally above the foot F² and the hinge G', so that its tendency is to lift the hinged frame E into the vertical position, substantially parallel to the headboard of the bed. The hinged frame E is adapted to stand either in a vertical, inclined, or horizontal position. One or more cords H, applied to the end of said frame opposite the headboard, are used for drawing the hinged frame downward into the position shown by said Fig. 1. When drawn down into the said position, said cord may be secured to the foot-board of the bed by any suitable means, as the hook H'. When said cord is released, the spring F again lifts said frame and the netting supported thereby into the upright position. Figs. 2 and 3 show more fully the construction of said hinged frame. The frame is composed of the two side arms E² and the connecting end piece E³. These three parts

may consist of a single piece or they may be distinct and their meeting ends suitably joined to each other. The drawings show such union formed by means of coiled-wire tubes E⁴. 5 Such a union is shown in detail by Fig. 3. The coiled-wire tube E⁴ has an internal diameter equal to the external diameter of the parts E² and E³. The adjacent ends of the parts E² and E³ have peripheral notches e³, 10 into which a portion of the coils e⁴ of the coiled tube E⁴ may fall, thus locking said parts E² and E³ within said coiled tube. Said coiled tube being made of a good quality of spring-wire, said tube becomes amply strong for forming such a union. At one end of said coiled tube the wire is turned downward below the periphery of said tube and formed into a hook E⁵, as shown in the right-hand portion of Fig. 3, which portion is an end view of the coil 15 shown in plan in the other portion of said figure. Said hook E⁵ is used as an attachment for the cord H, by which said hinged frame is drawn downward, as already described. The lower end of each part E² of said hinged 20 frame is bent horizontally toward the other part, so as to form two hinge-arms E⁶, directed toward each other. Said arms E⁶ extend into or through the sleeve E⁷ on the lower part of the plate G. Thus the hinge of said frame 25 is formed. (See Figs. 1, 4, 5, and 6.) A nut E⁸ may be applied to the free end of the arm E⁶ to retain said arm in position; but such retention may usually be effected by the engagement between the parts E² and the coils 30 F³ of the spring F adjacent to the foot F². Each arm E⁶ is preferably placed between the coils F³ and the bed and in front of the foot F², so that the portion of the spring F between 35 said foot and the coils F³ may form a stop, limiting the rearward movement of the hinged 40 frame E. A bracket J extends rearward from said plate G and is provided with a vertical aperture J', through which one of the members D' of the head-rest of the canopy-support 45 extends. Said aperture is located far enough rearward to allow said member D' to clear other portions of said plate G, to the end that said member may be moved up and down 50 in said aperture to adjust the height of the upper portion of said member to varying needs. A set-screw J² extends through said bracket J into the aperture J' and bears against said member, thus binding the member at any chosen elevation. In Figs. 5 and 55 6 said plate G is shown as having on the upper portion of its inner face a horizontal groove G², adapted to receive one of the horizontal portions of the foot F². Figs. 4 and 6 60 show four holes extending through said plate G in lines perpendicular to the plane of said plate. Of these four holes the two marked g and g² are in a vertical plane cutting the plate G centrally and are intended to receive wood-screws passing into a wooden headboard of a 65 bedstead, while the holes marked g⁴ and g⁵ are in a horizontal plane and separated a distance approximately equal to the thickness

of a metallic bed-post and intended to receive bolts when said plate is to be secured to a post of a metallic bedstead.

Fig. 9 shows a horizontal section through the plate G and through a cylindric post L, to which said plate is applied. Said plate is applied to one side of said post, and a band L' extends around the opposite side of said post, and said plate and band are drawn toward each other by screw-bolts L² and L³, the foot F² resting between said plate and said post L.

The mosquito-netting extends over the head-support D, the frame E, the cords H, and the sides of the bedstead.

I claim as my invention—

1. In a canopy-support, a spring having one end folded to form a base or foot having its parts lying substantially in the same plane, and the portion of said spring next to said foot being formed into one or more coils, F³, resting in a plane to which said foot is lateral, said coils being on a horizontal axis parallel to and at such distance forward of the plane of said foot as to make said plane tangential to said coils, substantially as described.

2. In a canopy-support, a spring having one end folded to form a base or foot having its parts lying substantially in the same plane, and the portion of said spring next to said foot being formed into one or more coils, F³, resting in a plane to which said foot is lateral, said coils being on a horizontal axis parallel to and far enough forward of the plane of said foot to make said plane tangential to said coils, and said spring having its other end shaped to engage a side rod of a canopy-frame, substantially as described.

3. In a canopy-support, the combination of a spring having one end folded to form a base or foot having its parts lying substantially in the same plane, and the portion of said spring next to said foot being coiled in a plane to which the plane of said foot is perpendicular, suitable means for securing said foot to a bedstead, or other article, and a side rod hinged adjacent to and engaged by said spring, substantially as described.

4. In a canopy-support, the combination of a spring having one end folded to form a base or foot having its parts lying substantially in the same plane, and the portion of said spring next to said foot being coiled in a plane to which the plane of said foot is perpendicular, and a bracket engaging said foot, and a side rod hinged adjacent to and engaged by said spring, substantially as described.

5. In a canopy-support, the combination of a spring having a foot in a plane perpendicular to the plane in which said spring acts, a bracket for engaging said foot, and a hinged side rod located adjacent to and engaged by said spring, substantially as described.

6. In a canopy-support, the combination of a spring having one end folded to form a base or foot having its parts lying substantially in the same plane and the portion of said spring

next to said foot being coiled in a plane to which the plane of said foot is perpendicular, and a bracket engaging said foot, and a side rod hinged to said bracket and engaged by 5 said spring, substantially as described.

7. In a canopy-support, the combination of a spring having one end folded to form a base or foot having its parts lying substantially in the same plane, and the portion of said spring 10 next to said foot being formed into one or more coils, F^3 , resting in a plane to which said foot is lateral, said coils being on a horizontal axis parallel to and far enough forward of the plane of said foot to make said 15 plane tangential to said coils, and a bracket for engaging said foot, and a side rod hinged to said bracket and engaged by said spring, substantially as described.

8. In a canopy-support, the combination of 20 a spring having one end folded to form a base or foot having its parts lying substantially in the same plane, and the portion of said spring next to said foot being coiled in a plane to which the plane of said foot is perpendicular, 25 said spring having its other end shaped to engage a side rod of the canopy-frame, and a bracket engaging said foot and having a hori-

zontal aperture parallel to said bracket, and a side rod hinged in said aperture and engaged by said spring, substantially as described. 30

9. In a canopy-support, the combination of a spring having one end folded to form a base or foot having its parts lying substantially in the same plane, and the portion of said frame next to said foot being formed into one or 35 more coils, F^3 , resting in a plane to which said foot is lateral, said coils being on a horizontal axis parallel to and far enough forward of the plane of said foot to make said plane tangential to said coils, said arm having its other end shaped to receive a side rod of the canopy-frame, and a bracket engaging said foot and having a horizontal aperture parallel to said bracket, and a side rod hinged in 40 said aperture and engaged by said spring, 45 and a vertical aperture, and a vertical rod located in said aperture, substantially as described.

In testimony whereof I affix my signature in presence of two witnesses.

WILLIAM P. BIDDLE.
